UNITED STATES PATENT OFFICE.

HUBBARD C. WEST, OF MOUNT VERNON, NEW YORK.

LUBRICANT-RETAINING CAP FOR TIMERS.

1,351,818.

Specification of Letters Patent.

Patented Sept. 7, 1920.

Application filed July 22, 1919. Serial No. 312,558.

To all whom it may concern:

Be it known that I, HUBBARD C. WEST, a citizen of the United States, residing in Mount Vernon, in the county of Westchester and State of New York, have invented certain new and useful Improvements in Lubricant-Retaining Caps for Timers, of which the following is a specification.

This invention relates to timers for automobile engines or the like, and has for its object to provide means for adapting the timer casing to hold oil therein for retaining the contacts substantially in a bath of oil and for preventing the gumming of oil therein or arcing.

Other objects of the invention will appear as the description proceeds; and while therein minute details of the invention are described, the invention is not limited to these, since many and various changes may be made without departing from the scope of the invention as claimed.

In the accompanying drawing, showing by way of example one of many possible embodiments of the invention,

Figure 1 is an axial vertical sectional view, partly in elevation, showing a timer with my invention applied thereto;

Fig. 2 is a side elevation of a baffle disk for preventing the throwing of the oil from the timer; and

Fig. 3 is an elevation, showing the inner side of the timer.

The timer is shown as applied to an engine having a timing shaft 5 and engine casing 6, the latter provided with the usual centering ring 7 coaxial with the timing shaft 5. Disposed over the end of said timing shaft and fitting around said centering ring is the commutator casing 10 provided with a depression 11 for receiving the usual casing clip (not shown) for holding the casing in place.

Around the inner face of said casing is disposed an insulating fiber ring 12 in which is embedded a plurality of contacts comprising contact plates 13 and contact bolts 14, the latter extending radially through said fiber ring and casing and held in place by means of retaining nuts 15. These bolts are adapted to receive the usual binding nuts (not shown).

Fixed on the timing shaft is a bracket collar 18 provided with a pair of perforated brackets 19, between which are pivotally mounted a pair of fork members 20 forming

a roller fork having spaced outer end prongs 21 between which is mounted a contact roller 23 adapted to engage the contact plates 13 as the timing shaft rotates.

Within the open side of said commutator casing is a convexed disk-shaped oil cap 25 having its outer edge disposed between said rings 7 and 12 frictionally secured in said casing in an oil-tight manner. The oil cap is provided with a large opening 26 receiving the timing shaft and having its center disposed directly above the center of the cap.

The lower edge of said opening is disposed as near as practicable to the center of the cap, thereby forming a large oil retaining space or basin in the lower part of the casing.

For preventing the throwing of oil from the casing by the action of the moving parts of the timer, there is provided a baffle disk 30 disposed between the cap 25 and the collar 18, and almost closing said opening. Said baffle disk is provided with a central flanged opening snugly receiving the timer shaft whereby the disk is held in place.

An inspection of Fig. 3 will show that the opening 26 is large enough to permit the timer cap 25 and the casing 10 to be withdrawn over the disk 30 and the movable members of the device without removing the disk or said members from the shaft or the timer cap 25 from the casing.

If desired, the timer cap may be made integral with the casing or it may be soldered or otherwise fixedly or removably held in place.

The timer itself may be of any usual or desired construction, and operates in the ordinary way.

Oil may be injected at the oil cap 31, and it is only necessary to inject a sufficient quantity of clean oil to maintain the efficient operation of the timer. As the cap 25 is secured oil tight in the casing, the oil-receiving basin formed thereby at the bottom of the casing is oil-tight and therefore leak-proof.

I claim as my invention:

1. In combination, a substantially horizontal shaft; a support for said shaft; a revoluble contact member on the shaft; a substantially axially horizontal casing movable relative to said support and disposed over the contact member and provided with an inner end-wall formed to permit passage for said shaft, the lower part of said casing and

end-wall together forming a leak-proof oil-retaining basin adapted to retain therein a pool of oil in which said member will dip; and contacts within said casing and engageable by said contact member.

2. In combination, a substantially horizontal shaft; a revoluble contact member thereon; a casing disposed over the member and formed with an opening for said shaft, and, in its lower part, with a leak proof oil-receiving basin adapted to hold therein a pool of oil in which said member will dip; and a baffle on said shaft within said casing and disposed over said opening.

3. In combination, a shaft; a casing disposed over the shaft and formed with an oil-receiving basin in its lower part and having an opening in its upper part; and a baffle disk on said shaft within said casing and partly closing said opening.

4. In combination, a commutator casing; an oil cap secured oil-tight in said casing and forming therewith an oil-receiving basin in the lower part thereof and leaving an opening in the upper part; and a baffle within said casing and partly closing said opening.

5. In combination, a timing shaft; a casing disposed over the timing shaft; contacts around the inner face of said casing; a movable contact on said shaft and adapted to contact said first named contacts; an oil cap secured in said casing and forming therewith an oil-receiving basin and leaving an opening at the upper part; and a baffle disk on said shaft and within said casing and partly closing said opening.

6. In combination, a timing shaft; a commutator casing disposed over the timing shaft; contacts around the inner face of said casing; a movable contact on said shaft and adapted to contact said first named contacts; and a convexed disk-shaped oil cap having its outer edge secured oil-tight in said casing and provided with a large opening receiving said shaft and having its center disposed above the shaft.

7. In combination, a timing shaft; a commutator casing disposed over the timing shaft; contacts around the inner face of said casing; a movable contact on said shaft and adapted to contact said first named contacts; a convexed disk-shaped oil cap having its outer edge secured oil-tight in said casing and provided with a large opening receiving said shaft and having its center disposed above the shaft; and a baffle disk disposed between said cap and movable contact and almost closing said opening and having a central opening snugly receiving said shaft.

8. In combination, a timing shaft; a commutator casing disposed over the end of the

timing shaft; an insulating ring around the inner face of said casing; a plurality of fixed contacts on the ring; a pivoted contact pivoted on said shaft and adapted to contact said fixed contacts; a disk-shaped oil cap secured oil-tight in said casing and provided with a large opening receiving said shaft and having its center disposed above the shaft; and a baffle disk disposed on said shaft between said cap and pivoted contact and almost closing said opening.

9. In combination, an engine having a timing shaft and a commutator centering ring; a commutator casing disposed over the end of the timing shaft and around said ring; an insulating ring around the inner face of said casing; a plurality of contacts comprising contact plates embedded in the inner face of said insulating ring; a contact pivoted on said shaft and adapted to contact said plates; a convexed disk-shaped oil cap having its outer edge disposed between said rings and secured oil-tight in said casing and provided with a large opening receiving said shaft and having its center disposed directly above the center of the cap; and a baffle disk disposed between said cap and contact almost closing said opening and having a central opening snugly receiving said shaft.

10. In combination, an engine having a timing shaft and a commutator centering ring thereon coaxial with the timing shaft; a commutator casing disposed over the end of the timing shaft and fitting around said ring and provided with a clip receiving depression at its outer part; an insulating fiber ring around the inner face of said casing; a plurality of contacts comprising contact plates embedded in the inner face of said insulating ring, and bolts secured to the plates and passing radially through the insulating ring and said casing; retaining nuts on said bolts; a collar fixed on said shaft and provided with a perforated bracket; a roller fork pivoted on said bracket and having spaced outer-end prongs; a contact roller mounted between said prongs and adapted to contact said plates; a convexed disk-shaped oil cap having its outer edge disposed between said rings and secured oil-tight in said casing and provided with a large opening receiving said shaft and having its center disposed directly above the center of the cap; and a baffle disk disposed between said cap and collar almost closing said opening and having a central flanged opening snugly receiving said shaft.

HUBBARD C. WEST.
